(57) **CLAIM**

The ornamental design of a hood for a vehicle, as shown and described.

DESCRIPTION

FIG. 1 is a top perspective view of a hood showing my new design, viewing the hood from the front left side, the right side being identical to the left side;

FIG. 2 is a top plan view thereof;

FIG. 3 is a front elevation view thereof; and,

FIG. 4 is a side elevation view thereof.

The bottom side of the hood that faces the vehicle engine compartment is omitted and forms no part of the claimed design.
